Otto R. Nemeth, Chicago, Ill., assignor to Products Development, Inc., Chicago, Ill., a corporation of Illinois

Application December 23, 1944, Serial No. 117,047

Term of patent 14 years

(Cl. D61—1)

To all whom it may concern:

Be it known that I, Otto R. Nemeth, a National of Czechoslovakia, residing at Chicago, in the county of Cook and State of Illinois, have invented a new, original, and ornamental Design for an Elevation Adjusting Device for Picture Projectors or the like, of which the following is a specification, reference being had to the accompanying drawing, forming part thereof.

Figure 1 is a front elevational view of an ele-

vation adjusting device for picture projectors or the like embodying my new design.

Fig. 2 is a side elevational view of the device.

Fig. 3 is a top plan view of the device.

I claim:

The ornamental design for an elevation adjusting device for picture projectors or the like, substantially as shown.

OTTO R. NEMETH.
